UNITED STATES PATENT OFFICE.

JULIUS FRANK, OF CHICAGO, ILLINOIS.

BAG-SEALING MACHINE.

Application filed July 26, 1926. Serial No. 124,925.

This invention relates to a machine which will fold the flap or free end portion of a container in the form of a bag, upon the body portion thereof, at the same time applying a suitable area of adhesive to one of the two side portions, and thereafter press the portions together under conditions which will cause them to adhere and effectively close the container; and the invention has for its object to provide an improved and more efficient and reliable apparatus for performing this operation.

The invention proceeds upon the principle of providing traveling aprons or belts, upon and between which the container to be closed and sealed, can be placed in upright position, and by which the container will be automatically fed past an adhesive applying device, then through a folding device, and finally between pressing rolls; one of said traveling members being mounted in a horizontal plane to afford vertical support to the container, and the others traveling in converging paths, around a pair of vertically presented pulleys, receive the container between them and hold it against tipping from its upright position. The adhesive applying means comprises a pair of disks revolving in contact with opposite sides of that portion of the container to which the adhesive is to be applied, one of said disks constituting a vehicle for applying adhesive and the other serving to sustain the container in contact with the applying disk; the sustaining disk being hollow or concave on its periphery through which it impinges against the container so that it slightly concaves the container and therefore renders it more rigid against flexing under the pressure of the applying disk; also a third disk constantly dipping in a receptacle containing adhesive, arranged to revolve upon an axis perpendicular to those of the disks first named, and present to the adhesive disk a measured supply of adhesive determined by the restricting capacity of a scraper with which the supply disk co-acts before reaching the adhesive applying disk. The folding means is in the form of a pair of curbs or rails between which that portion of the container, including the edges of the free end, which is concerned with the closure to be effected, is made to pass; one of said rails having a deflecting flange which gradually changes from a mere horizontally inclined edge, into

an overhanging portion and then into a grooved or inverted U-shaped portion, one depending wall of which completes the downward presentation or folding of the free end of the receptacle and presents it in position to be creased by the finishing rolls.

The invention consists in certain novel features of construction hereinafter fully explained and particularly pointed out in the claims.

In the accompanying drawings in which the preferred embodiment of the invention is shown by way of illustration,

Figure 1 is a top plan view of a sealing machine embodying the several features of the invention;

Figure 2 is a side elevation of the same;

Figures 3, 4, 5 and 6 are vertical transverse sections taken respectively on the lines 3^x—3^x, 4^x—4^x, 5^x—5^x and 6^x—6^x of Figures 1 and 2, Figures 5 and 6 being on an enlarged scale;

Figure 7 is a detail view of one of the folding curbs; and

Figure 8 is a detail view of one of the containers after the closure is completed.

1 represents an endless apron, mounted in a horizontal plane upon the idle guiding roller 2 and the driving roller 3, which latter is on a shaft 4 constantly driven by link belt 5 from a shaft 6 which is in turn driven through worm wheel 7 and worm 8 by a pulley 9 which receives its drive from any suitable source of power, such for instance as an electric motor 10. 11 represents a pair of vertical belts guided by the idle rollers 12, and by driving rolls 13 on shafts 14 and 15 which are geared together at 16, and one of which, for instance shaft 14, is continued downward and connected through miter gear 17, one gear wheel 90 of which is on the shaft 6 already referred to. Belts 11 while spaced apart by the rollers 12, at the intake end of the machine, are made to converge so that the container A, in the form of a bag or envelope placed upon the apron and guided in between said belts, would be gripped and caused to pass through the machine.

18 represents the sustaining disk, 19 the applying disk of an adhesive supplying means, mounted respectively upon vertical spindles 20 and 21 carrying sprockets 22 and 23 which are driven by chains 24 and 25 from sprockets 26 and 27 on the shafts 14 and 15 already referred to. Applying disk 110

19 revolves in constant contact with the supply disk 28 which dips into adhesive receptacle 29 and constantly carries adhesive to the applying disk, but only after the contacting portion of the supply disk passes through the slot of a scraper 30 the width of which slot is proportioned to prevent an excess of adhesive reaching the applying disk.

- means in the path of the bag, and in position to apply adhesive to a portion thereof above the belts, and folding and pressing means in position to act upon the bag in the order named after it passes the adhesive applying means.

10 31 and 32 represent the rails of a folding device, which rails, as shown more clearly in Figure 6, embody in their construction vertical webs 31^a and 32^a. Rail 31 is fashioned to provide a horizontal flange 31^b which projects across the upper edge of the rail 32, also a depending flange 31^c. The horizontal flange 31^b commences at the intake end of the folding device with a mere deflecting edge 31^d and merges thence into the horizontal flange 31^b so that the upstanding flap or free end of the container will be gradually deflected from vertical to horizontal position and then from horizontal to folded position, which is shown in Figure 6. With the parts 20 of the container in this position, the part bearing the adhesive will occupy about the position X so that if the container be now passed between the finishing rolls 33, and the folded parts of the container pressed together, a sealed closure of the container will have been completed. As shown in Figure 7, the rail 32 is constructed at its rear end with a longitudinal recess 32^b in position to avoid contact with the adhesive as the folding is completed. Finishing rolls 33 are mounted on the shafts 14 and 15 just above the driving pulleys 13 of the feed pulleys 11 and the area of the container which is concerned with the formation of its closure is all above the horizontal plane of said driving pulleys 13.

With an apparatus constructed as described, envelopes or bags A placed upon the endless apron 1 and manually sustained until they pass in between the feed belts 11 will be gripped by said pulleys at a level well below any portion of the container which is concerned with the formation of its closure, and by said pulleys fed past the adhesive applying means, then through the folding means, and finally to the finishing rolls when the folding and adhering of the closure-forming portions of the container as well as their compression into adhering relation will have been complete, and the resultant package will be ready for shipment.

I claim:

1. In a machine for sealing bags, means affording vertical support to a bag to be sealed, a pair of feed belts mounted to receive a bag between them and adapted to grip the bag and convey it through the machine in an upright position, with the portions of the bag to be folded and adhered projecting above said belts, adhesive applying

2. In apparatus for sealing bags, means affording vertical support to a bag to be sealed, a pair of belts embracing said bag on opposite sides and sustaining it in an upright position while feeding it through the machine, adhesive applying means in position to engage a portion of the bag above the belts, folding means in the path of the bag beyond the adhesive applying means and a pair of creasing rolls between which the bag is passed after leaving the folding means.

3. In apparatus for sealing bags, a traveling apron affording vertical support for bags, a pair of embracing and feeding belts above said apron, mounted to receive bags between them to feed the same through the machine, a pair of opposed disks between which bags are passed by said belts, one of which disks is provided with means for keeping its marginal portion supplied with adhesive, folding means located to engage portions of the bags above said belts, after the bags pass the adhesive applying means, and means for pressing together folded portions of the bags after they leave the folding means.

4. In a sealing machine for bags, means for feeding bags in upright position through the machine, adhesive applying means, and folding and pressing means; the adhesive applying means comprising a pair of horizontal disks in position to impinge against opposite sides of the bags, a vertical disk impinging against the periphery of one of said horizontal disks, and means for supplying a measured quantity of adhesive to said supplying disk. 100 105

5. In a sealing machine for bags, means for feeding bags in upright position through the machine, adhesive applying means, and folding and pressing means; the adhesive applying means comprising a pair of horizontal disks in position to impinge against opposite sides of the bags, a vertical disk impinging against the periphery of one of said horizontal disks, and means for supplying a measured quantity of adhesive to said supplying disk; said last named means comprising a receptacle for adhesive into which the vertical disk dips, a scraper which said vertical disk encounters after leaving the adhesive in said receptacle. 110 115 120

6. In a machine for sealing bags, means for feeding a bag in upright position through the machine, adhesive applying means positioned to encounter said bag as it passes through the machine, and folding and pressing rolls also in position to act upon the bag; 126

the adhesive applying means comprising a pair of horizontal disks co-acting on opposite sides from the bag, one of said disks having a hollow periphery adapted to develop a groove in the bag and the other of said disks having means supplying adhesive to its periphery. 25

7. In a machine for sealing bags, endless belt means for passing a bag in upright position through the machine, said endless belt-means being restricted in its contact with the bags to a level below the sealed portion of the bags, and folding means located to encounter the portion of the bag which is above the level of said endless belt-means in its passage through the machine; said folding means comprising a pair of rails between which the bag passes and a folding flange encountering the portion of the bag which extends above said rails and which embodies in its construction a deflected portion, a horizontal portion and a depending portion merging from one into another in the order named and which are

10

15

also above the level of said endless belt- means.

8. In a machine for sealing bags, means for passing a bag in upright position through the machine, and folding means located to encounter the bag in its passage through the machine; said folding means comprising a pair of rails between which the bag passes and a folding flange encountering the portion of the bag which extends above said rails and which embodies in its construction a deflected portion, a horizontal portion and a depending portion merging from one into another in the order named all of which portions are above the level of the means for passing the bag through the machine; said machine also having a pair of coacting pressing rolls also above said level and impinging on opposite sides of the folded portion of the bag as it leaves the folder.

Signed at Chicago, Illinois, this 21st day of July, 1926.

JULIUS FRANK.
